LIGHTER FOR GAS BURNERS

Clyde W. Mummery, Detroit, Mich., assignor to
The Midland Steel Products Company, Cleve-
land, Ohio, a corporation of Ohio

Application July 6, 1936, Serial No. 89,069

2 Claims. (Cl. 158—115)

This invention relates to new and useful im-
provements in lighters for gas burners and the
like.

An important object of the invention is to pro-
vide a lighter for range top gas burners and the
like which will also light an oven burner.

More particularly it is an important object
of the invention to provide for the temporary
trapping of a body of combustible gas or vapor
from the source of supply whereby the several
lighter tubes may be completely filled with the
gas for immediate and automatic ignition upon
completion of the gas trapping action.

Another more specific object of the invention
is to provide an automatic lighter for gasoline
pressure stoves which requires no constant con-
sumption of gas vapor due to the arrangement
providing for the generating burner as a pilot
light.

A still further object of the invention is to
provide special lighter tubes which retard the
flow of gas therethrough and cooperate in the
gas trapping action for the purpose of achieving
a longer flash of flame from each lighter tube
and consequently more positive automatic light-
ing of the burners.

Other objects and advantages of the invention
will become apparent during the course of the
following description.

In the accompanying drawings forming a part
of the application and wherein like numerals are
employed to designate like parts throughout the
several views,

Fig. 1 is a top plan, somewhat diagrammatically
of the invention applied to range burners, the
source of supply of which, is also connected to
an oven burner,

Fig. 2 is an enlarged plan of a part of the
lighter,

Fig. 3 is a section of the same taken on the
line 3—3 of Fig. 2 showing it applied to a gas
manifold of a gasoline pressure stove.

Fig. 4 is an enlarged section of a part of a gas-
oline vapor manifold illustrating another form
of absorption material disposed therein for pre-
cluding white smoky flames from the burners,
and

Fig. 5 is an enlarged longitudinal section of a
portion of one of the lighter tubes.

Perhaps the most widely used form of auto-
matic lighter for gas ranges operating upon nat-
ural and manufactured gas, employs one pilot
light which is constantly burning at a point equi-
distant from the four range top burners.
Through this pilot is projected four streams of

gas from the supply to cause elongated flames to
extend from the pilot to the four burners. In
ranges including baking ovens, a constantly burn-
ing pilot within the oven in proximity to the
oven burner is required, as the distance from
the pilot to the oven burner is too greater to per-
mit the projection of a flame from the pilot light
on the range top into the oven.

There have been proposed lighters for range
top burners which cause the gas to flow from the
burner to be lighted to the pilot to be ignited and
cause a flash back to the burner.

With the present invention it is proposed to
trap a quantity of gas or gasoline vapor from the
main supply pipe to reduce its pressure and sub-
sequently ignite the gas whereby a flash across
all burners including the oven burner is obtained
with the use of only a predetermined quantity
of gas or gas vapor.

While the present invention may be employed
in conjunction with natural or manufactured gas
with slight modifications in the arrangement,
it has been illustrated in the present instance
for use in conjunction with gasoline pressure
burners which include a gasoline vapor generat-
ing tube G having an atomizing valve, not shown,
to which gasoline is fed through a pipe I and air
through pipe H. The generator is disposed above
an elongated generator burner GB and enters
a carburetor C where it mixes with air and is
then discharged into a distributing chamber D
connected to a distributing manifold M for the
open range burners B and oven burner design-
ated OB. The individual arms of the distrib-
uting manifold M are each provided with a valve
as shown in dotted lines controlled by rotary
valve stems designated R for the rear open burn-
ers, F for the front open burners and O for the
oven burner. The carburetor C is provided with
an air intake opening C' and in this depending
portion of the carburetor is positioned an absorb-
ent pad or material 6 to absorb any liquid fuel
which may get into the carburetor for preventing
the appearance of white smoky flames at any of
the burners.

The generator burner is supplied with gasoline
vapor from the distributor by the conduit P.
A sponge or other absorbent material 7 is also
disposed in the bottom of distributor D and sim-
ilar material may be disposed in the manifold 50
at advantageous points where condensation of
gaseous vapor is apt to occur. In Fig. 4 a modi-
fied form of absorbent pad 8 is illustrated as
being cylindrical and fastened to the bottom of
the distributor by means of a cap screw 9 pass- 55

ing through the center of the pad and through a metallic perforated shield or screen 10 embracing the same.

The lighter of the present invention includes 5 a two piece housing, the front part 11 of which is a closed chamber detachably connected by bolts 13 to the other part 12 forming a valve casing. A pair of dished metal screens 14 separate these two parts of the housing and are 10 positioned in the joint between the parts as illustrated in Fig. 3. This screen is preferably of a type to prevent any back fires from the lighter chamber, 11 into the manifold.

The valve chamber portion of the housing is 15 provided with a pair of integral laterally extending attaching ears for connecting the housing to the open top of the distributing chamber or to any desired portion of the manifold M. The valve chamber is provided with an annular internal valve seat 16 having a restricted passage 20 therethrough and upon which a sliding valve 17 is normally seated by means of a coil spring 18 bearing against a removable plug 19 in the extreme end of the valve chamber. This coil 25 spring is preferably loaded sufficiently to prevent any explosion in the lighter chamber 11 from unseating the valve and entering the fuel supply manifold. The bottom of the valve chamber is provided with an aperture 20 to permit the passage 30 of fuel from the manifold into the valve chamber 12. In gasoline pressure stoves as well as those employing natural or manufactured gas, the fuel in the manifold or supply pipe is of course under pressure and when the valve 17 is 35 moved against the tension of spring 18 by the valve operating rod 21, fuel under pressure passes the valve seat, the screen 14 and into the lighter chamber 11. The valve operating rod 21 passes through the forward end of the lighter chamber 40 and is extended toward the front of the stove to be provided with an operating valve button or handle L in a plane with the handles of burner valves.

In order to conduct the gas vapors from the 45 lighter chamber 11 to a point in proximity to the respective burners D, lighter tubes 22 communicate with the chamber 11 in air tight fashion through the side walls thereof and radiate therefrom as shown best in Fig. 1. To convey the gas 50 vapor from the chamber 11 to a point inside the oven and in proximity to the oven burner OB, a tube 23 extends from the side of the chamber 11 in communication therewith to be attached in any suitable manner whereby the flash of gas therefrom will traverse the oven burner causing ignition 55 when the oven burner valve C is open. All of these tubes 22 and 23 are provided with gas retarding means and this means may be provided by corrugating or otherwise roughening the interior surfaces of tubes 22 and 23. However, in 60 the preferred embodiment each of these lighter tubes 22 and 23 is composed of flexible conduit material formed by spirally winding the section shown in overlapping relation with packing cord 65 and between the overlapped portions, as shown clearly in Fig. 5. This obviously provides the interiors of the tubes with lateral pockets which effectively retard the flow of gas therethrough. The outer ends of the lighter tubes 22 may be 70 supported in any suitable manner in proximity to the burners D so that the burning gas therefrom will extend substantially diametrically across each burner B. All of these lighter tubes are preferably arranged with respect to the chamber 75 11 so as to receive the gaseous vapor from the

manifold in the least amount of time when the valve 17 is open.

In order to ignite the gas in the lighter chamber 11 and lighter tubes at the proper time, a short tube 24 extends in air tight fashion into the 5 lighter chamber 11, preferably through the bottom thereof, while its free end is of reduced cross section and is supported above the generator burner GB under the generating tube G in any suitable manner. Consequently, tube 24 forms, in 10 effect, a continuation of any of the lighter tubes due to all of them communicating with the interior of the lighter chamber 11.

The operation of the form of invention disclosed herein is as follows: This setup being for a 15 gasoline pressure burner, it is understood that gasoline and air are fed to the generator tube G under pressure in controlled quantities so that the liquid gasoline is highly vaporized as it passes through the carburetor C and into the distributing 20 chamber D. From this chamber, the vaporized gas is free to pass through the pipe P into the generating burner, which is lighted to maintain the operation of the other burners. The heat from this generating burner heats the generator 25 tube G and assists further in the vaporization of the fuel, which as before stated, passes from the distributing chamber into the manifold M and to the respective burners ready for ignition. It is of course essential for the generating burner to be 30 continually burning, and as such, forms a pilot light which constantly burns at the outlet end of tube 24. To light any selected burner, its valve, controlling the flow of gasoline vapor thereto, is opened to allow gas to flow from the manifold 35 through the slits or apertures in the burner so as to be ignited as soon as a spark or flame is created in proximity thereto. For this purpose, the valve rod 21 is forced inwardly thereby lifting valve 17 from its seat 16 and permitting gasoline 40 vapor under pressure to enter the valve chamber, pass the seat 16 screen 14 to fill the lighter chamber 11 and each of the tubes 22 and 23 all the way out to their respective burners. By reason of the disposition of the pipes 22, 23, and 24 the 45 lighter tubes are permitted to become completely filled with gasoline vapor during the momentary opening of valve 17 because this gasoline vapor is under pressure. Accordingly, the operator only holds the valve 17 open momentarily and the gasoline vapor at the free end of tube 24 is ignited by the generator burner flame, but does not pass into chamber 11 due to the pressure and velocity of gas entering through valve 17. However, as soon as this rod 21 is released and the spring 50 18 closes valve 17, the pressure and velocity no longer keeps the flame at the end of tube 24, and accordingly, spontaneously, the gas in the chamber 11 and the tubes 22 and 23 is ignited in 55 somewhat of a slight explosion so that the burning gases are forcibly ejected from the free ends of these five tubes across the burners to ignite whichever one or more has been turned on prior thereto. In spite of the distance of the oven burner from the lighter chamber 11, nevertheless 60 a very elongated flash of flame is projected from the tube 23 across the oven burner due to the fact that this tube has been filled with gas or combustible vapor prior to the flame at the end of tube 24 igniting the entire body of gas in the 65 chamber upon closing of the inlet valve 17.

It will be understood that various changes in the size, shape and arrangement of parts may be resorted to without departing from the spirit of 70 75

the invention or the scope of the appended claims.

I claim:

1. In an oven and open top range stove having oven and open top burners, a supply manifold for gas under pressure, a pilot remote from the oven burner, an explosion chamber at substantially the center of the open range top and remote from the oven burner and connected with the manifold, a starter pipe connected to said chamber and having its free end disposed near the pilot, lighter tubes having pocketed side walls and radiating from the chamber to all burners to entrain or trap gas therein admitted from the combustion chamber, a normally closed valve closing off the chamber from the gas supply manifold, and valve operating means adapted to momentarily open the valve to permit the gas from the manifold to fill the chamber, lighter tubes and starter pipe and then to close the valve to promote an explosion from the pilot through the starter pipe and chamber into all of the lighter tubes to all burners simultaneously.

2. In an oven and open top range stove having oven and open top burners, a supply manifold for gas under pressure, a pilot remote from the oven burner, an explosion chamber terminating at one end in a valve chamber communicating with the manifold, anti-back fire means between said chambers, a valve normally cutting off communication between said chambers, a starter pipe connected to said chamber and having its free end disposed near the pilot, lighter tubes having pocketed side walls and radiating from the chamber to all burners to entrain or trap gas therein admitted from the combustion chamber, and a manual push rod slidably mounted in the combustion chamber and adapted to open the valve to permit the gas from the manifold and valve chamber to fill the chamber, lighter tubes and starter pipes and then to close the valve to promote an explosion from the pilot through the starter pipe and chamber into all of the lighter tubes to all burners simultaneously.
